UNITED STATES PATENT OFFICE.

JOSEPH H. DOLD, OF PHILADELPHIA, PENNSYLVANIA,

EXTENSION TABLE.

Application filed May 24, 1926. Serial No. 111,120.

This invention relates generally to extension tables, the invention having more particular reference to a novel type of extension table.

5 The invention has for an object the provision of an improved extension table of simple construction and novel arrangement of parts.

For further comprehension of the invention, and of the objects and advantages thereof, reference will be had to the following description and accompanying drawings, and to the appended claims in which the various novel features of the invention are 15 more particularly set forth.

Fig. 1, of the drawings, is a side elevational view of my improved extension table, partly in section.

Fig. 2, is a vertical sectional view taken 20 on the line 2—2 of Fig. 1.

Fig. 3, is an enlarged fragmentary view, partly in section, illustrating certain detail construction of my improved extension table.

25 Fig. 4, is a similar view to that shown in Fig. 2, but illustrating a modification of my improved extension table.

Fig. 5, is a side elevational view, partly in section, of the modification of my improved 30 extension table, as illustrated in Fig. 4.

Fig. 6, is an enlarged side elevational view of the top supporting member, as used in combination with the modification of my improved extension table.

35 Fig. 7, is an enlarged bottom view of the locking device as used in connection with my improved extension table.

Fig. 8, is an enlarged side elevational view partly in section illustrating a modification of my improved extension table.

40 Fig. 9, is a vertical sectional view taken on the line 9—9 of Fig. 8.

Fig. 10, is a similar view to Fig. 7 showing a modification.

45 As here embodied my improved extension table comprises legs 10, of any suitable shape and design, provided with elongated slots 11, at their upper extremities adapted to receive a tongue 12 of the side members 13 and the cross members 14, so as to rigidly support the legs 10, said legs 10 being further supported by triangular shaped members 15, positioned adjacent to the legs 10 and to the side members 13 and to the 55 cross members 14.

The main table top 16, is attached to the

side members 13 and is positioned at the center of the side members 13. The extension members 17, or leaves, have attached thereto at their outer edges, finishing strips 18, of 60 any suitable shape.

The spacing strips 19 are attached to the extension members 17, at or near their outer edges, adjacent to the finishing strips 18, the supporting members 20, are attached to the spacing strips 19, and extending forward therefrom under the extension members 17, and having an enlarged extremity 21, tapered, as at 22, the latter described construction being such as will permit the extension members 17 to be pulled outward or extended. It is to be understood that when the extension members 17, are pushed inward or closed, that the inner edge 23 of the extension members 17, will be raised over 75 the main table top 16.

Referring in particular to Fig. 7, of the accompanying drawings, the slidable members 24, are slidably mounted, as at 25, in apertures suitably located in the cross members 14, and have attached at their outer extremities a knob 26, the engaging members 27, are pivotally attached at their inner extremities, as at 28, to the inner extremities of the slidable members 24. The above described construction being such as will permit the free extremities 29 of the engaging members 27, to be pushed or forced through apertures 31, suitably located in the supporting members 20, and to engage the depending members 30, attached to the main table top 16, when the knob 26 is pushed or forced inward, so as to hold the extension members 17 in an extended position, it being understood that the slidable members 24 and the engaging members 27, will normally assume a disengaged position, as designated by the dash and dot lines 32 and 33, respectively.

Referring in particular to Figs. 4 and 5 of the accompanying drawings, in which I have shown a modification of my improved extension table, the table top support 34, is attached to the side members 13, and is positioned at the center of the side members 13. The main table top 35, is attached to the table top support 34, and extends beyond the table top support 34, on both sides thereof, as clearly shown in Fig. 5 of the accompanying drawings. The extension members 36, are attached to the outer extremities of the top supporting members 37, which are 110

provided with an extended element 38, extending below, or slightly downward therefrom, and provided with an extended member 39, extending downward therefrom. 5 The top supporting members 37, are slidably positioned in elongated slots 40, formed in the cross members 14.

The above described construction is such as will permit the extension members 36, 10 to be pulled outward, so as to extend the extension members 36, it being understood that when the extension members 36 are pushed inward, or closed, that the main table top 36, will be raised slightly upward, 15 so as to permit the extension members 36 to slide under the main table top 35.

Referring in particular to Figs. 8 and 9 in which I have illustrated a further modification of my improved extension table, 20 the levers 41, are pivotally attached to the cross members 14, as at 42, and are positioned directly below the supporting members 20. The above described construction is such as will permit the levers 41, when 25 forced upward as designated by the dot and dash lines 43, to raise the extension members 36, above the main table top 16, so as to permit the extension members 36 to be pushed inward or closed.

30 In Fig. 10 the engaging members 27' are provided with slots 27^a adapted to receive pins 28' which are fastened to the table.

Having thus described my invention, what I claim as new and desire to protect by Letters Patent of the United States is as follows:

1. In an extensible table of the class described comprising a frame and legs for supporting the same, a stationary top mem-

ber mounted on said frame, extensible members mounted on said frame adapted to be positioned in the plane of said stationary top member, cleats secured to the bottom of said extensible members having recesses in the inner ends thereof, a rod slidably mounted in 45 the end member of said frame, levers pivotally mounted on the ends of said rod adapted to be extended and retracted by movement of said slideable rod for engaging the ends of said levers in the recesses of said cleats for retaining said extensible member in a predetermined position.

2. In an extensible table of the class described, a stationary top member supported by the sides of said table, extensible top members adapted to be positioned above said stationary top member and to rest thereupon, said extensible members being adapted to be extended relative to each other and disposed in the plane of said top member, cleats secured to the bottom of said extensible member adapted to support the same when in an extended position and to engage the bottom of said stationary top member for retaining said extensible members superimposed above 60 said stationary top member when the extensible members are in retracted position, a rod slidably mounted in the end member of said frame, levers pivotally mounted on the ends of said rod adapted to be extended and 70 retracted by movement of said slideable rod for engaging the ends of said levers in the recesses of said cleats for retaining said extensible member in a predetermined position.

In testimony whereof I have affixed my 75 signature.

JOSEPH H. DOLD.
